CLAIM

The ornamental design for a lighting fixture as shown and described.

DESCRIPTION

FIG. 1 is a top perspective view of a lighting fixture;
FIG. 2 is a bottom perspective view of the lighting fixture;
FIG. 3 is a right side view of the lighting fixture;
FIG. 4 is a left side view of the lighting fixture;
FIG. 5 is a front view of the lighting fixture;
FIG. 6 is a rear view of the lighting fixture;
FIG. 7 is a top view of the lighting fixture; and,
FIG. 8 is a bottom view of the lighting fixture.
Broken lines in the drawings represent features of the lighting fixture that form no part of the claimed design.

1 Claim, 4 Drawing Sheets
